UNITED STATES PATENT OFFICE

ALBERT H. NICKERSON, OF PAWTUCKET, RHODE ISLAND

POST ANCHOR

Application filed October 12, 1929. Serial No. 399,281.

This invention relates to certain new and useful improvements in post anchors and while the post is illustrated in the accompanying drawings for the support and display of a real estate sign or board, it is understood that the invention is of considerably broader aspects, the primary object being to provide a ground anchored post of any character, such as sign posts, fence posts, poles or any shaft adapted for ground anchoring.

An important object of this invention is to provide a ground anchored post wherein the ground entering end of the post has a spear shaped head secured thereto with ground anchor arms associated with the lower end of the post to prevent removal of the post from the ground by their cooperation with the post head and rendered inoperable upon partial rotation of the post to permit removal of the post from the ground.

A further object of the invention is to provide a post anchor of the type above set forth wherein means is associated with the post and ground line to prevent rotation of the post for unauthorized removal.

With the above and other objects in view that will become apparent as the nature of the invention is better understood, the same consists in the novel construction, combination and arrangement of parts to be hereinafter described in detail and then claimed.

In the accompanying drawings showing the preferred embodiment of the invention and to which reference is had by like characters designating corresponding parts throughout the several views;

Figure 1 is a side elevational view of a post equipped with the improved ground anchor constructed in accordance with the present invention, the post being illustrated as anchored in the ground with the sign plate carried by the upper end thereof shown in front elevation,

Figure 2 is another side elevational view of the post showing the sign plate in edge elevation,

Figure 3 is a detail vertical sectional view taken on line 3—3 of Figure 1,

Figure 4 is a horizontal detail sectional view taken on line 4—4 of Figure 2,

Figure 5 is a horizontal sectional view taken on line 5—5 of Figure 1, showing the device attached to the post and engaged with the ground line to prevent unauthorized rotation of the post to effect its removal,

Figure 6 is a fragmentary side elevational view of the lower end of the post showing the spear head shaped anchor foot attached to the lower end of the post with the ground anchor arms extended to their horizontal operative positions, the arms being illustrated by dotted lines as vertically disposed and by full lines in the position assumed when the post is set into the ground,

Figure 7 is a fragmentary side elevational view of the lower end of the post showing the post and spear head shaped foot rotated through an arc of 90° relative to the ground anchor arms and supporting collar therefor with the pivoted ends of the arms displaced from engagement with the side shoulders of the spear head shaped foot and assuming depending positions at the sides of the foot for removal from the ground,

Figure 8 is a fragmentary side elevational view taken at the opposite side from the showing in Figure 6,

Figure 9 is an enlarged detail sectional view taken on line 9—9 of Figure 6 showing the cross pin connection between the post and foot and the collar through which the post extends and showing the flat sides of the foot,

Figure 10 is an enlarged detail sectional view taken on line 10—10 of Figure 8 showing the inclined or tapering side edges of the spear head shaped foot and the abutments on the pivoted ends of the ground anchor arms engaged with side shoulders at the upper end of the foot,

Figure 11 is an enlarged horizontal detail sectional view taken on line 11—11 of Figure 6,

Figure 12 is an enlarged horizontal detail sectional view taken on line 12—12 of Figure 6, and

Figure 13 is a detail sectional view, similar to Figure 12 showing the post and anchor foot shifted through an arc of 90° from the posi-

tion shown in Figure 12 and illustrating the side shoulders of the anchor foot that retain the anchor arms in their operative horizontal positions.

Referring more in detail to the accompanying drawings, and particularly to Figures 1 to 5 there is illustrated a ground anchored post 1 having a ground anchoring foot 2 at its lower end, a ground line plate 3 to prevent rotation of the post while a sign plate or board 4 is carried by the upper end of the post, and as previously stated, it is to be understood that the post may be used in various connections and is not intended to be limited 15 for the display of a real estate sign or board.

The post 1 is illustrated as being of tubular construction with a cap 5 mounted upon its upper end, the sign plate 4 being secured to the post through the medium of rivets 6 or 20 other fastening devices passing through the post and plate with spacer blocks 7 interposed between the post and plate.

The ground anchor for the post is shown more clearly in Figures 6 to 13, the lower end 25 of the tubular post 1 receiving the tang 8 of the spear head shaped foot 9, the foot being anchored in the lower end of the post by the cross pin 10 that has its opposite ends 10^a projecting beyond the sides of the post as 30 clearly shown in Figure 9. The spear head shaped foot 9 has parallel side faces 11 in the same plane as the outer face of the post 1 while the opposite side edges 12 incline or taper upwardly from the lower point 13 toward the base of the tang 8 to provide side shoulders 14 extending outwardly of the post 1. The tapering edges 12 of the foot are continuous from end to end while the parallel side faces 11 of the foot taper at their lower 35 portions as at 11^a to the point 13 of the foot as shown in Figure 9. As previously described, the foot 9 is anchored to the post 1 by the cross pin 10 and upon rotation of the post, the foot moves therewith.

A collar 15 is rotatably mounted upon the lower end of the post 1 and is engaged with the abutment shoulders 14 of the anchor foot and has opposite sides at the upper edges cut away as at 16 into which the end extensions 50 10^a of the cross pin 10 project which prevents upward movement of the collar 15 upon the post 1, but permits limited rotation thereof, the cutaway portions 16 defining stop shoulders 17 and 18 on the collar. Pairs of spaced 55 diametrically opposite apertured lugs 19 are carried by the collar 15 adjacent the shoulders 17 and pivotally support upon the cross pin 20, the inner ends of ground anchor arms 21. Each arm 21 has a flattened side adjacent its 60 pivot end to provide an abutment 22 for flat contact with the shoulder 14 upon the spear head shaped foot 9 to retain the arms in operative horizontal positions as shown in Figures 6 and 10.

In setting and anchoring the post 1 in the

ground G, the sinking of the post may be aided by the initial boring or excavation of an opening or hole, the arms 21 being vertically disposed as shown in Figure 6. The post is driven into the ground to the desired depth and upon slight upward movement thereof, the outwardly beveled ends 21^a of the arms bite into the ground and cause the arms to be shifted to a horizontal position and resist further upward movement of the post, the abutments 22 on the arms limiting downwardly swinging movements thereof by contact with the shoulders 14 upon the foot. To prevent the post 1 and head 9 from rotation for displacement of the arm abutment from contact with the shoulders, a disk plate 23, shown in Figures 1, 2 and 5 has a central boss 24 anchored to the post 1 by the rivet 25, angle arms 26 carried by the disk plate 23 being forced into the ground G as shown in Figure 1 to prevent rotation of the post and foot. When it is desired to remove the post from the ground, the rivet 25 or similar fastening for anchoring the disk plate 23 to the post is destroyed to permit free rotation of the post through the disk plate and upward movement thereof. The post 1 and foot 9 are then rotated through an arc of 90°, the rotation being limited by the shoulders 17 and 18 on the cutaway portions of the collar 15, the collar and arms 21 remaining stationary as the arms are embedded in the ground. When the post and foot are so rotated, the shoulders 14 upon the foot 9 are displaced from the abutments 22 of the arms 21 with the flat sides 11 of the head 9 disposed beneath and inwardly of the pivot pins 20 of the arms as shown in Figure 7 and at which time upward movement of the post will permit downward pivotal movement of the arms and free removal of the post from the ground. It will therefore be seen that the post is securely anchored in the ground against unauthorized removal and that it is necessary to destroy the connection between the ground plate 3 or disk 23 and the post 1 to permit removal of the post.

From the above detailed description of the invention it is believed that the construction and operation will at once be apparent, and while there is herein shown and described the preferred embodiment of the invention it is to be understood that such changes may be made therein as will fall within the scope of the invention as claimed.

What I claim is:

1. A post anchor comprising a post, a foot fixed thereto having side shoulders disposed laterally of the post, a collar on the post above the shoulders and ground anchor arms pivoted on the collar to engage the shoulders when horizontally positioned to prevent removal of the post from the ground, a pin for securing the collar to the post, said collar having edge cutaway portions defining 120

spaced shoulders and the ends of the pin extending beyond the post into the cutaway portions to engage the shoulders for limiting rotary movement of the post and foot.

2. A post anchor comprising a post, a foot fixed thereto having side shoulders disposed laterally of the post, a collar on the post above the shoulders and ground anchor arms pivoted on the collar to engage the shoulders when horizontally positioned to prevent removal of the post from the ground, the sides of the foot between the shoulders being in the same plane as the post whereupon rotation of the post and foot, the arm may pivot downwardly, a pin for securing the collar to the post, said collar having edge cutaway portions defining spaced shoulders and the ends of the pin extending beyond the post into the cutaway portions to engage the shoulders for limiting rotary movement of the post and foot.

3. A post anchor comprising a post, a foot fixed thereto having side shoulders disposed laterally of the post, a collar on the post above the shoulders and ground anchor arms pivoted on the collar to engage the shoulders when horizontally positioned to prevent removal of the post from the ground, a pin for securing the collar to the post, said collar having edge cutaway portions defining spaced shoulders and the ends of the pin extending beyond the post into the cutaway portions to engage the shoulders for limiting rotary movement of the post and foot and means on the post engaging the ground to prevent rotation of the post and foot.

4. A post anchor comprising a post, a foot fixed thereto having side shoulders disposed laterally of the post, a collar on the post above the shoulders and ground anchor arms pivoted on the collar to engage the shoulders when horizontally positioned to prevent removal of the post from the ground, the sides of the foot between the shoulders being in the same plane as the post whereupon rotation of the post and foot, the arm may pivot downwardly, a pin for securing the collar to the post, said collar having edge cutaway portions defining spaced shoulders and the ends of the pin extending beyond the post into the cutaway portions to engage the shoulders for limiting rotary movement of the post and foot and means on the post engaging the ground to prevent rotation of the post and foot.

5. A post anchor comprising a tubular post, a foot having a tang entering the lower end of the post and being of spear head shape with diametrically opposite side shoulders outwardly of the post, a collar through which the post is rotatable resting on the shoulders, a pin extending through the post and tang above the collar to retain the collar on the post and ground anchor arms pivoted on the

collar to be limited by the shoulders in downward pivotal movements.

6. A post anchor comprising a tubular post, a foot having a tang entering the lower end of the post and being of spear head shape with diametrically opposite side shoulders outwardly of the post, a collar through which the post is rotatable resting on the shoulders, a pin extending through the post and tang above the collar to retain the collar on the post and ground anchor arms pivoted on the collar to be limited by the shoulders in downward pivotal movements, and said pin and collar cooperating to limit rotary movement of the post and foot for displacing the foot shoulders from abutting engagement by the arms.

In testimony whereof I affix my signature.

ALBERT H. NICKERSON.
